 C. Hodges, doing business as Champion Aviation
 Products Company, Los Angeles, Calif., a
 co-partnership

Application July 17, 1941, Serial No. 402,740

11 Claims. (Cl. 74—9)

My invention relates to starter mechanism, and more particularly to starter mechanism for aircraft, and other appropriately geared engines within the capacity of the starter mechanism.

An object of the invention is to provide in starter mechanism, a straight, splined shaft for the purpose of advancing the gear engaging portion of the starter mechanism, and to eliminate spiral splines or grooves. Spiral grooves tend to permit chattering of groove engaging members, which is desired to be eliminated in the present invention.

Other objects of the invention are to provide starter means for aircraft that is sturdy and affords an even pull, that is positive in operation, convenient in use, easily installed in a working position, and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a longitudinal section through starter mechanism embodying the features of the present invention, taken on the line 1—1 of Fig. 5.

Fig. 2 is a broken elevation of a part of Fig. 1, partly in section.

Fig. 3 is a view similar to Fig. 2, but showing a different operative position.

Fig. 4 shows a succeeding operative position, following that shown in Fig. 3.

Fig. 5 is a transverse section taken on the line 5—5 of Fig. 1.

Referring more in detail to the drawing, the reference character 6 generally designates an engine having a rotary end-faced gear 7. The clutch elements 8 of the gear 7 are disposed to be engaged by clutch elements 9 on a movable head 10. The head 10 has an integral hollow collar 25 that is slid upon a hollow shaft 13.

The head 10 is internally grooved to fit upon splines 14 of the shaft 13, as best shown in Fig. 5. A relatively weak spring 15 is connected to tend to hold the head 10 away from the gear 7 of the engine. The spring 15 is mounted in the hollow portion 16 of the shaft 13 and abuts at one end against a screw plug 17, in the hollow portion 16, of the shaft 13, and at the other end

abuts against a head 18 on a bolt 19 slideable in the plug 17. A sleeve 20 on the shank of the bolt 19 limits compression of the spring 15. A nut 21 on the bolt 19 contacts the outer face of a washer 22. Through the intermediary of the mechanism described, the spring 15 tends to draw the washer 22, and thereby the head 10, away from the engine 6. It is to be understood that the washer 22 abuts the outer face of the movable head 10.

The collar 25 has a reduced shank 23 whose external face is smooth and slideable within a ring 24.

The collar 25 is provided with angularly arranged abutting faces 26 and 27, which are arranged to engage abutting faces 28 and 29, respectively, on pointed integral lugs 30 on the ring 24. Similar abutting faces and similar lugs are provided on the side of the mechanism opposite to that shown.

The ring 24 is free to rotate upon the shank 23 of the head 10, except for limitations by the abutting faces 26 and 27 upon the lugs 30. However, a series of springs 31 is mounted on an inner face of a cylindrical flange 32 of a shell 33. The outer ends of the springs 31 are bolted to the flange 32, as suggested at 33. The inner ends of the springs 31 have curved tips 34 which frictionally engage the circumferential surface of the ring 24. An inner race 35 and an outer race 36 for bearings 37 mount the shaft 13 for rotation within the shell 33.

Clutch plates 38 and 39 alternately engage ribs 40 on the shaft 13 and ribs 41 within the shell 33. A nut 42 upon the shaft 13 provides a fixed abutment for the clutch plates. A movable head 43 is urged, by means of a spring 44, to cause the plates 38 and 39 to frictionally engage with one another. A nut 45, also on the shaft 13, maintains a washer 46 in position on the shaft, and provides a fixed abutment for the spring 44. A gear 47, likewise mounted on the shaft 13, is driven by starter motor mechanism (not shown). A bearing 48 aids in supporting the shaft 13.

In the operation of the mechanism, the starter motor drives the gear 47, which in turn rotates the shaft 13. Rotation of the shaft 13 causes the therewith engaged head 10 also to rotate. However, the rotation of the clutch elements 9 in a counter-clockwise direction, looking at same in the direction of the arrow A, causes the abutment faces 27, on the collar 25, to engage the abutment faces 29 on the pointed lugs 30. Due to the inclined arrangement of the faces 27 and 29, the collar 25 and thereby the head 10 are

moved outward upon the shaft 13, as best shown in Fig. 3.

When the head 10 has been moved outward to the position shown in Fig. 3, the clutch elements 9 engage the clutch elements 8 on the engine and turn the engine over. As soon as the engine 6 is operating by its own combustion, the inclined surfaces 51 behind the clutch elements 8, engage the inclined surfaces 49 behind the clutch elements 9 and thereby push the starter head 10 away from starting position. Fig. 4 shows the starter head 10 returned to its original position after the engine 6 has been started.

There is considerable tension upon the collar 24 by means of the springs 31; in fact, there must be enough tension by means of these springs to hold the head 10 against rotation upon rotation of the shaft 13. However, as soon as the engine 6 is rotating, there must be sufficient resilience in the springs 31 to permit the head 10 to retract and slide inward with regard to the flange 32.

The clutch provided by the plates 38 and 39 affords a safety means in case of the kick-back of the engine 6. The nut 45 may be adjusted to regulate the tension of the spring 44, which in turn regulates the friction between the plates 38 and 39.

It is believed clear that the present starter mechanism is reversible by merely changing the direction of the clutch elements 8 and 9.

The spring 15 is a relatively weak spring and not strong enough to move the head 10 inward with respect to the flange 32 against the action of the springs 31, which are relatively stronger, at least in their aggregate, than the relatively weak spring 15.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. In starter mechanism, a shaft having straight splines longitudinally thereof, a starter head meshing with the splines on the shaft and having a longitudinal sliding movement with respect to the shaft, the starter head having an inclined portion, an element normally substantially stationary during forward movement of the starter head, the element having inclined means arranged to engage the inclined portion of the starter head and to feed the starter head forward, upon rotation of the starter head by means of the shaft.

2. In starter mechanism, a shaft having straight splines longitudinally thereof, a starter head having a rearwardly extending member provided with an inclined end face facing rearwardly with respect to said member, the starter head meshing with the splines on the shaft and having a longitudinal sliding movement with respect to the shaft, an element normally substantially stationary during forward movement of the starter head, the element engaging the inclined portion of the starter head and arranged by reason of such inclined portion to feed the starter head forward, upon rotation of the starter head by means of the shaft.

3. In starter mechanism, a shaft having straight splines longitudinally thereof, a starter head having an abutment face, the starter head meshing with the splines on the shaft and having a longitudinal sliding movement with respect to the shaft, an element normally substantially stationary during forward movement of the starter head, the element having inclined means arranged to engage the abutment face of the starter head and to feed the starter head forward, upon rotation of the starter head by means of the shaft.

4. In starter mechanism, a shaft having straight splines longitudinally thereof, a starter head meshing with the splines on the shaft and having a longitudinal sliding movement with respect to the shaft, the starter head having a rearwardly extending collar provided with an inclined portion spaced inward from the end of the collar, an annular element upon the collar to the rear of the inclined portion but engaging with the inclined portion, and means arranged to maintain the element substantially stationary during forward movement of the starter head.

5. In starter mechanism, a shaft, a starter element connected to rotate with the shaft but having a movement lengthwise with respect to the shaft, an element arranged to be held relatively stationary during forward movement of the starter element, at least one of the elements having an inclined portion and the other element having an abutting face engaging the inclined portion on the other element, arranged to effect said forward movement of the starter element by rotation of the shaft, and means disposed frictionally to substantially prevent movement of the second mentioned element during rotation of the shaft effecting forward movement of the starter element.

6. In starter mechanism, a shaft having straight splines longitudinally thereof, a starter element meshing with the splines on the shaft and having a longitudinal sliding movement with respect to the shaft, an element arranged to be movable during return movement of the starter element, at least one of the elements having an inclined portion and the other element having an abutting face engaging the inclined portion on the other element, arranged to effect forward movement of the starter element by rotation of the shaft, and means disposed frictionally to substantially prevent movement of the second mentioned element during rotation of the shaft effecting forward movement of the starter element.

7. In starter mechanism, a shaft, a starter element connected to rotate with the shaft but having a movement lengthwise with respect to the shaft, an element arranged to be held relatively stationary during forward movement of the starter element, at least one of the elements having an inclined portion and the other element having an abutting face engaging the inclined portion on the other element, arranged to effect said forward movement of the starter element by rotation of the shaft, and resilient means disposed to resiliently resist movement of the second mentioned element during rotation of the shaft effecting forward movement of the starter element.

8. In starter mechanism, a shaft having straight splines longitudinally thereof, a starter element meshing with the splines on the shaft and having a longitudinal sliding movement with respect to the shaft, an element arranged to be movable during return movement of the starter

element, at least one of the elements having an inclined portion and the other element having an abutting face engaging the inclined portion on the other element, arranged to effect forward movement of the starter element by rotation of the shaft, and resilient means disposed to resiliently resist movement of the second-mentioned element during rotation of the shaft effecting forward movement of the starter element.

9. In starter mechanism, a shaft, a starter element connected to rotate with the shaft but having a movement lengthwise with respect to the shaft, an annular element arranged to be movable during return movement of the starter element, at least one of the elements having an inclined portion and the other element having an abutting face engaging the inclined portion on the other element, arranged to effect forward movement of the starter element by rotation of the shaft, the annular element having a circumferential face of substantially the same diameter throughout its length, providing a substantially smooth outer surface, and resilient means frictionally engaging the said outer surface of the annular element and resisting movement of such element during rotation of the shaft effecting forward movement of the starter element.

10. In starter mechanism, a shaft, a starter element connected to rotate with the shaft but having a movement lengthwise with respect to the

5 shaft, the starter element having a rearwardly extending collar, an annular element rotatable upon the collar, at least one of the elements having an inclined portion and the other element having an abutting face engaging the inclined portion on the other element, arranged to effect said forward movement of the starter element by rotation of the shaft, and resilient means frictionally engaging the said outer surface of the 10 annular element and resisting movement of such element during rotation of the shaft effecting forward movement of the starter element.

11. In starter mechanism, a shaft, a starter element connected to rotate with the shaft but having a movement lengthwise with respect to the shaft, relatively weaker spring means tending to move the starter element along the shaft away from its engine-starting position, a relatively movable element normally substantially stationary during rotation of the shaft, at least one of the elements having an inclined portion and the other element having an abutting face engaging the inclined portion on the other element, arranged to effect said forward movement of the starter element by rotation of the shaft, and relatively stronger spring means than the first-mentioned spring means resiliently resisting rotation of the second-mentioned element during rotation of the shaft.
